United States Patent Office

Des. 221,520
Patented Aug. 24, 1971

221,520

COMBINED BOTTLE AND OVERCAP THEREFOR

James E. Plummer, Toledo, Ohio, assignor to Owens-Illinois, Inc., Toledo, Ohio

Filed July 17, 1970, Ser. No. 24,008

Term of patent 14 years

Int. Cl. D9—01

U.S. Cl. D9—130

FIG. 1

FIG. 2

FIG. 4

FIG. 1 is a perspective view of a combined bottle and overcap therefor showing my new design;

FIG. 2 is a front elevational view, the opposite side being the same in appearance as the side shown;

FIG. 3 is a side elevational view, the opposite side being the same in appearance as the side shown; and

FIG. 4 is a top plan view thereof.

I claim:

The ornamental design for a combined bottle and overcap therefor, substantially as shown and described.
